UNITED STATES PATENT OFFICE

EUGEN PRESTINARI, OF IRVINGTON, NEW JERSEY, ASSIGNOR TO GEMEX COMPANY, A CORPORATION OF NEW JERSEY

EXPANSION BRACELET

Application filed October 27, 1930. Serial No. 491,382.

This invention relates to an expansion bracelet, and has for its object to provide a bracelet which is flexible in a longitudinal direction, and is also flexible sidewise or at right angles to its length.

A further object of this invention is the provision of a bracelet having large openings between its marginal edges and along the length thereof which is elastically extensible in the direction of its length.

A still further object of this invention is the provision of a unit construction having spaced elastic portions, one of which portions may be moved or elastically extended without a corresponding extending movement of the other portion, whereby a lateral curve may be effected.

A still further object of this invention is the provision of a series of units having a plurality of independently extendible portions which may be detachably connected to a similar unit to form a series of units in a chain.

With these and other objects and advantageous features in view, the invention consists of a novel arrangement of parts more fully disclosed in the detailed description following, in conjunction with the accompanying drawing, and more particularly set forth in the appended claims.

In the drawing:

Fig. 1 is a top plan view of a series of units of my improved construction connected together and in collapsed or contracted position;

Fig. 2 is a view similar to Figure 1 showing the units in extended or expanded position;

Fig. 3 is a view similar to Figure 1 but showing relative different expansion of the different marginal edges of the bracelet;

Fig. 4 is a perspective view of the inner member of one of the units;

Fig. 5 is a perspective view of one of the outer members which comprise the unit;

Fig. 6 is a sectional view with the bottom portion of one of the units removed;

Fig. 7 is a section on line 7-7 of Figure 6;

Fig. 8 is a section on line 8-8 of Figure 1;

Fig. 9 is a section on line 9-9 of Figure 1;

Fig. 10 is a side elevation of the chain; and

Fig. 11 is a view similar to Figure 10 but showing one of the units as being detached from the next unit.

It has been found desirable to provide bracelets having large openings therein to prevent heating of the wrist when worn, and with this end in view, bracelet links of a generally rectangular open frame shape have been joined together with their openings permitting view of the wrist therethrough, and the circulation of air about the wrist; and I have provided such a construction which is elastically extendible, wherein each unit of the same may be elastically extended so that the same may be passed over the hand of the wearer from the wrist in removing the watch from position, and in order that the bracelet may be more easily removed from the wrist, I have formed the construction in such a manner that it will be flexible sidewise as well as longitudinally, which is of great advantage when being passed over the hand of the wearer; and the following is a detailed description of the present embodiment of this invention, illustrating the preferred means by which these advantageous results may be accomplished.

With reference to the drawing, I have shown a plurality of units detachably connected together. The units are of identical construction and are each composed of a generally H-shaped blank 12 which may be considered as having inner or frame-shaped members 13 connected by an integral lateral extending bar 14. The frame-shaped members are each slotted longitudinally as at 15 with a portion of the removed stock raised at one end 16 to form an abutment. The slot 15 is enlarged at its opposite end 17 to receive the hook of the slide or outer link of the next adjacent unit. About each portion 13 of each unit there is mounted an outer link 18 of generally band-shaped construction having a top wall 19 with a hook 20 formed at one end, and a tongue 21 extending from the opposite end of the top wall and closing the hook as at 22. The top wall 19 is domed upwardly, as illustrated in Figures 5 and 9.

to form a hollow portion 23 to slidably receive the abutment 16 of the member 13, and a spring 25 acts between the abutment 16 and the folded portion 24, between the top 5 wall 19 and the tongue 21 to yieldingly move the outer link 18 to cause the major portion of the slide member 13 to house therein.

Each of the units thus consists of the frame or slide members 13 housed within a pair 10 of outer links 18 which is slidable relative thereto, and with opposite slide members connected by an integral bar 14 between the frames 13. These units may be detachably connected together by the hooks 20 of the 15 outer links passing through the openings 17 in the frames, as illustrated in Figures 10 and 11 to detachably connect them together and permit yielding expansion of the bracelet longitudinally, or as each of the outer 20 links 18 is independent with reference to its opposite outer link of the unit, one edge of the bracelet construction may be expanded to a greater extent than the other edge, as illustrated in Figure 3, rendering a 25 very flexible construction sidewise.

Another way of considering this structure is that of two separate elastically extendible chains having inner and outer slidable units with one of the members, that shown in this 30 case being the inner member of each unit connected together, thereby attaching the chains in spaced relation, the attaching bars of which of course may be of any width or spaced apart themselves if desired to permit 35 of greater open work in the chain as a whole.

While I have described certain construction forms which embody the principles of my invention, it is obvious that other desired changes in arrangement may be made within 40 the spirit and the scope of the invention as defined in the appended claims.

I claim:

1. A bracelet comprising a series of links each having a pair of frame members with 45 laterally extending means for connecting said frame members together, and a second series of pairs of links independent of each other joining said pairs of members and each movable independently with reference to the 50 frame members of said links and means acting within said independent links for urging the links to contracted position.

2. A bracelet comprising a series of links each having a pair of frame members with 55 laterally extending means for connecting said frame members together, a second series of opposite pairs of links joining said pairs of members and slidably with reference thereto, and means acting between said frame members and pairs of links for yieldingly urging 60 said series of links into contracted position.

3. A bracelet comprising a series of links each having a pair of spaced frame members with an integral laterally extending bar 65 therebetween, and pairs of spaced generally

band-shaped links connecting said frame members and slidable relative thereto, and yielding means acting between said frame and band shaped links for moving said links into contracted position, but permitting 70 yielding longitudinal expansion thereof.

4. A bracelet comprising a pair of series of inner links connected together with a laterally extending bar, housing links for each of said inner links slidable relative 75 thereto, and connecting said inner links together, and a spring in said housing link acting between said links tending to move said inner link to housed position.

5. A bracelet comprising a pair of series of inner links connected together with a laterally extending bar and each having an abutment adjacent one end, housing links for each of said inner links slidable relative 80 thereto, and connecting said inner links together, and a spring in said housing link acting between said abutments and said housing links tending to move said inner links to housed position and means for detachably 85 connecting said housing links to said inner links.

6. A bracelet comprising a pair of series of inner links connected together at their middle portions with a laterally extending 90 bar leaving the end portions of the links laterally unconnected and each of said inner links having a guide abutment adjacent one end, housing links for each of said inner links slidable relative thereto, and connecting said 95 inner links together, and a spring in said housing link acting between said abutment and said housing links tending to move said inner link to housed position, and said abutment engaging with the inner surface of said housing link to guide said inner link in its 100 sliding movement.

7. A bracelet comprising two spaced longitudinal series of units, each unit having a rigid inner link and a rigid outer link in slidable relation, each outer link of one unit being hingedly connected to the longitudinally adjacent inner link of the next unit on one side and each inner link of said first mentioned unit being hingedly connected to the longitudinally adjacent outer link of the next unit on the opposite side, and said series of units being inter-connected through said inner links.

8. A bracelet comprising a series of links, each link having a pair of spaced frame members with an integral laterally extending bar therebetween, there being a longitudinal slot in each of said members, a second series of links in said slots interconnecting the first series of links, and means for yieldingly maintaining both series of links in normally contracted position.

In testimony whereof I affix my signature.
EUGEN PRESTINARI.
